[57] **CLAIM**

The ornamental design for a holder for positioning work pieces in a welding relation, substantially as shown and described.

DESCRIPTION

FIG. 1 is a front perspective view of a holder for positioning work pieces in a welding relation showing my new design;

FIG. 2 is a top plan view thereof shown on a reduced scale;

FIG. 3 is a bottom plan view thereof shown on a reduced scale;

FIG. 4 is a front elevational view thereof shown on a reduced scale;

FIG. 5 is a side elevational view thereof with a vise plier being shown in broken lines for illustrative purposes only.

FIG. 1

FIG. 2

FIG. 3

FIG. 4

FIG. 5
